AERATION HOOD

John T. Marvin, Fairview Village, and Birchard L. Matthews, Cleveland, Ohio, assignors to The Patrol Valve Company, Cleveland, Ohio, a corporation of Ohio

Application May 19, 1934, Serial No. 726,528

3 Claims. (Cl. 158—115)

This invention relates to an improved burner bowl and aeration hood for use on gas or like range burners, and particularly concerns the provision of aeration means on such bowl to direct and limit the flow of secondary air to the associated burner.

The present novel burner bowl and aeration hood are particularly applicable in connection with flash tube ignition devices, in which the burner end of the flash tube is provided with a gas jet for directing the flow of gas in the initial or lighting stages into the tube toward a constant pilot. So as to insure the correct lighting of the burner by the flash tube device, the forward end of the latter must be positioned closely adjacent the gas burner within the burner bowl, and hence the normal purpose of the secondary air directing means through the hood destroys the useful function of the gas jet of the flash lighter device. In other words, the creation of an air draft as provided by the directing means of the bowl in the proximity of the burner end of the flash lighting tube causes the gas passing through the jet therein to be drawn towards the burner and away from the tube. This naturally defeats the required supply of gas interiorly of the gas tube, and in some instances after the gas has been lighted and the flash tube jet is also ignited, this jet flame will be extinguished by the secondary air draft and raw gas will then be fed from the jet to the space between the burner and the bowl.

This invention has for its primary object to provide additional means in the form of an aeration hood associated with the bowl and injection end of the flash lighter tube, whereby to overcome the tendency of the secondary air draft within the burner bowl and to obviate the aforesaid detrimental effects of such secondary air current upon the gas jet within the lighter tube.

In the accompanying drawing wherein like reference numbers include like parts,

Figure 1 is a plan view of a burner assembly showing the aeration hood and,

Figure 2 is a section on the line 2—2 of Figure 1.

Figure 3 is a section on line 3—3 of Figure 2.

In the drawing 10 indicates the burner bowl open at the top and having a bottom opening 11, in which is mounted the burner 12. This gas burner has a gas chamber 13 supplied with gas mixed with primary air in a mixing tube (not shown), from which a slot opening 14 permits the egress of gas for the burner flame. Above

slot 14 is an additional slot 15 communicating with a central open passageway 16 by means of ports 17. From this slot 15 secondary air is drawn to assist in supporting the flame of the burner. Additional secondary air is drawn through the bottom opening 11 in the burner bowl outside of the burner which aids the other secondary air coming through the slot 15 and increases the efficiency of the burner. It will be readily understood that as the burner heats up a much greater current of secondary air is drawn through both opening 11 and slot 15, so that the current obtains substantial velocity.

The burner 12 has a projection, 18 hollowed out to communicate with gas chamber 13 and a port 15 is provided in this projection 18. Into the port is projected the stem of a jet 20 supported on the end of flash tube 22. The jet 20 has an opening 23 from which gas may flow whenever it is flowing from burner slot 14. The flash tube 22 communicates with a pilot 24 so that gas injected from opening 23 may travel through the flash tube 22 to the pilot 24 where it ignites and flashes back through the tube to the burner 12 to ignite the gas issuing from slot 14. As soon as the jet has been ignited the flashing will end, but the jet of gas at 23 will remain ignited in a very small flame, secondary air for which is provided by an opening 26 in the bottom of the flash tube. This functioning of the herein disclosed flash lighter device is characteristic to the same, and a detailed description may be found in our copending application, Serial No. 711,972, filed February 19, 1934.

It will be evident from an understanding of devices of the present character that a current of air passing through the opening 11 in the burner bowl attains considerable velocity, and when the burner end of the flash lighter tube is placed within this air current the latter is sufficient to create a draft around the flash lighter tube end, and thus draw toward the burner the gas emitted from the port 23. It has been stated in the foregoing that in order to insure proper flash lighting of the burner the jet 20 must be arranged close to the burner port 14. This consequently places the jet 20 and flash tube 22 directly in the secondary air current, and before the present novel invention the use of flash lighters in connection with burner bowls had been very unsatisfactory. To prevent the flow of secondary air, as above discussed, from blowing out the small flame at 23 or from drawing the gas injected in tube 22 away from pilot 24 so

that flashing cannot occur, and permitting the escape of raw gas, the burner bowl 10 is provided with an aeration hood 25. This hood is shown as integral with the burner bowl 10, but it will be readily understood that it could be made separate therefrom. This hood is shaped so as to cover the end of the flash tube and the jet 23, (see Fig. 3), and to deflect the current of secondary air flowing upwardly from opening 11 away from the end of the flash tube, so that this air current does not act to draw the gas injected at 23 out of the tube to prevent same from passing through the tube to pilot flame 24. The hooded portion 25 is of sufficient size to overlie the burner end of the flash tube of jet 20 and to prevent the air passing upwardly around the projection 18 from creating a draft at the flash tube openings. Without the hood 25, the secondary air within the bowl would accentuate the secondary air coming through the port 26 and thus draw the same outwardly of the flash tube into the bowl and away from the pilot 24. The hood 25, by reason of the deflection of the secondary air from the flash tube, is found to effectively prevent the aforesaid difficulty. The slot 11 is relatively small so that the air passing therethrough attains a substantial velocity. It is believed that these theories of operation are combined in the success of this aeration hood. The theories are set out here to facilitate understanding of the device rather than limit the manner of its operation.

In the above detailed description our invention in a new aeration hood is embodied in a particular type heat concentrating burner bowl, and the advantages incident to such an arrangement are believed to be clearly defined. The invention also contemplates the adaptation of the new aeration plate to many types of burners and associated heat concentrating elements. It should, perhaps, be stated that flash tubes of the character illustrated, and others known and commonly used, have been more or less successful in gas range assemblies wherein the burners do not have the equivalent of a burner bowl or heat concentrating plate. The present economic trend, however, is to obtain the maximum efficiency from gas burners and a satisfactory means is found in the aforesaid heat concentrating device which is normally positioned closely adjacent the burner flame so as to prevent the downward circulation of heat from flame. As has been explained, when this plate is used it requires an opening between the same and the burner to supply the necessary secondary air. Several conditions result from this construction which render impractical the use of flash lighting devices in the heat zone or in the zone of the secondary air current. If a flash lighter device be so used and without means equivalent to the present novel aeration hood, it should be quite obvious that the raw gas emitted from the gas jet cannot follow its normal path up the flash tube toward the pilot light. Accordingly, in every instance, the flash ignition is materially delayed and in some instances completely destroyed.

In addition to the above functions, the hood acts as a means to prevent objects spilled from the stove top from clogging the flash tube or its

jet 23. This is an important feature of the invention, since the operation of the lighter depends upon having a clear tube and clean jet.

It will thus be seen that this invention has provided a means for correcting a very serious difficulty heretofore interfering with the use of flash ignition on ranges having burner bowls. It is to be understood that the device is applicable to all ranges having similar means to control the direction of the heat flow or secondary air flow. It is to be further understood that while a slot type burner has been shown this showing was merely for illustration, since the device is just as applicable to any other type burner of which other type, the familiar star type burner might be mentioned. It is applicable with other types of flash tube igniters than the one shown since in practically all of them an injection port is provided from the burner which injection port is intended to remain ignited whenever the burner is in operation. It is further applicable to protect any auxiliary flame that is to be supported in the normal path of secondary air flow.

Having described the invention what is claimed is:

1. In combination, a gaseous fuel burner and an igniter of the flash lighter type therefor, said burner having an auxiliary gas port for supplying gas to said lighter and adapted to support a flame during the operation of the burner, a dish-shaped concentrator bowl surrounding said burner and having a hole in its bottom of sufficient size to provide a secondary air space between the bowl and burner, said bowl having a lateral hole through its side to receive the burner end of said flash lighter device, and shielding means on the inside of said bowl adjacent said lateral hole, said shielding means extending internally of the bowl and enclosing the upper portion of the flash lighter projected inwardly of said bowl.

2. As an article of manufacture, a concentrator bowl for gas burners, said bowl being of general dish-shape and having a central opening in its bottom portion adapted to receive a burner therein, such opening being of sufficient size to provide an air space between said burner and portion of the bowl comprising said opening, and said bowl having a substantially radially extending portion on its inside, said radial portion comprising a substantially inverted semi-cylindrical shield projecting interiorly of the bowl toward the burner and adapted to cover the burner end of a flash lighter tube for said burner.

3. As an article of manufacture, a concentrator bowl for ring type gas burners, said bowl being of general dish-shape and having a central annular opening in its bottom portion adapted to receive a burner therein, such opening being of sufficient size to provide an air space between said burner and opening, said bowl having a lateral hole in its side, and an integral portion on said bowl comprising a shielding element extending from the inside of said bowl adjacent said hole inwardly thereof toward said burner whereby to provide means for receiving and shielding the burner end of a flash lighter tube for said burner.
